(57) **CLAIM**

The ornamental design for a drag chain conveyor beam, as shown and described.

DESCRIPTION

FIG. 1 is a top-front perspective view of a drag chain conveyor beam, showing the design;

FIG. 2 is a top plan view, the bottom being an identical image thereof;

FIG. 3 is a front side view, the rear side being an identical image thereof; and,

FIG. 4 is a left side view, the right side being an identical image thereof.

The broken lines in the drawings depict portions of the drag chain conveyor beam that form no part of the claim.

The conveyor beam has been shown with a symbolic break in its length. The appearance of any portion of the drag chain conveyor beam in the drawings between the break lines form no part of the claim.

1 Claim, 4 Drawing Sheets
